UNITED STATES PATENT OFFICE.

HENRY POFFINBARGER, OF TOLEDO, OHIO.

SPRING-FORMING MACHINE.

1,118,046.

Specification of Letters Patent. Patented Nov. 24, 1914.

Application filed April 9, 1913. Serial No. 760,077.

To all whom it may concern:

Be it known that I, HENRY POFFINBARGER, a citizen of the United States, residing at Toledo, Lucas county, Ohio, have invented 5 new and useful Spring-Forming Machines, of which the following is a specification.

This invention relates to forming articles, particularly the leaves of springs.

This invention has utility when embodied 10 in a forming machine for humped or camel-back springs, as the spring above the rear axle in Ford automobiles.

Referring to the drawings: Figure 1 is a fragmentary plan view of an embodiment 15 of the invention in a spring forming machine; Fig. 2 is a side elevation of the assembled leaves forming a spring as adapted to be produced by the invention herein; Fig. 3 is a fragmentary side elevation of 20 the forming machine of Fig. 1; Fig. 4 is a plan view, with parts broken away, of one of the anti-friction forming elements; and Fig. 5 is a fragmentary side elevation of the anti-friction end of the former of Fig. 4.

25 The forming machine may be actuated by the handle 1 mounted on the shaft 2 extending through the machine frame 3. Mounted on the shaft 2 is the crank arm 4 which with the link 5 forms a toggle for thrusting into 30 holding position the second toggle comprising the links 6, 7. Adjustment of the link 5 permits regulation of the throw limit past locking position or dead center. Rigid with the frame 3 is the top bed frame 8 to which 35 the link 6 is pivoted. Extending through the frame 8 are the guide rods 9 coacting with the brackets 10 fixed to the lower side of the movable former mounting 11 disposed to oppose the fixed former mounting 12 40 rigid with the frame 8. The fixed former 12 carries the fingers 13 to sustain the material to be formed, as spring leaves 14 placed on edge thereagainst and threaded on the adjustable stem or pin 15 carried by the 45 block 16.

The fixed mounting 12 has bolt openings 17 and slots 18 therein to receive bolts 19 which may have their nuts 20 lock the plates 21 down upon the adjustable forming elements 22, disposed to converge on their after side, or away from the movable former mounting. These elements are interchangeable friction former means, which may be disposed, as permitted by the holes and slot, 50 to determine the contour of a humped or

camel back spring having extensions therefrom.

The movable former mounting 11, which is connected to be actuated by the link 7 and its toggle connections, has openings 17 and slots 23 for bolts 19, so that their nuts 20 may force plates 21 to hold the forming elements 24, 25, 26, in adjusted positions.

In their thrust forward by throwing the handle 1, the former means 24, 25, 26, have 55 provision for yielding action by having the stems 27 extending into recesses 28 in the opposing or extension sections 29 as held spaced from the sections 24, 25, 26, by the compression springs 30 surrounding the 70 stems 27. The forming means or elements at the hump section of the spring have their extension sections 29 carry the anti-friction rollers 31, while the contour sections extending away from the hump have the movable 75 forming elements 24 provided with the friction actuating faces on their extensions 32. The anti-friction actuating faces 31, in operation by direct movement toward the stock to be formed roll it into the desired shape, 80 and notwithstanding the force brought to bear on the hot stock, there is no twisting or strain introduced to cause trouble in the completed article. The adjustments permit resetting for the different leaves of the 85 spring, which may be run through in series to advantage. A feature contributing materially to the effectiveness of the device, is the disposal of the forming element at the angle, element 26, somewhat in advance of 90 the adjacent friction element 24, 32, thereby forming a departure at this point from spring contour, which departure is an insurance in rolling the leaves to form to prevent friction tearing or undesirable crowding. The disposal of the movable forming elements to converge with the fixed formers permits a mutual reinforcement of the elements in relatively stiffening each other. The advance travel of the element 26 at the 100 angle, gives it greater compression when the machine is moved to closed or forming position to hold the hot stock sufficiently long that it may set.

What is claimed and it is desired to secure 105 by Letters Patent is:

1. A stretch eliminating spring forming machine embodying opposing yokes, driving means for effecting relative movement between the yokes to form a spring therebe- 110

2

tween, a plurality of elements in the first of said yokes directed toward the other yoke, said elements provided with forming ends outlining a spring to be formed with an abrupt bend theretoward, a plurality of elements in the second yoke directed toward the first yoke and held by the second yoke against relative movement laterally of the first yoke, said elements in the second yoke 5 provided with forming ends departing from outlining the spring to be formed by increased projection into the abrupt bend, and a yieldable mounting for the elements in the second yoke whereby they may be forced 10 backward independently of each other in the forming action which allows the spring being formed to move to shape without stretching at the abrupt bend.

2. A spring forming machine embodying 15 opposing yokes, driving means for effecting relative movement of the yokes toward each other to form a spring therebetween, forming means in the first of said yokes outlining a spring to be formed with an abrupt bend contour, a plurality of forming elements in 20 the second yoke directed toward the first

yoke and held by the second yoke against movement laterally of the relative travel of the yokes toward each other, one of said elements in the second yoke opposing the abrupt bend contour departing from the contour of the abrupt bend as outlined by the first yoke forming means by projecting in advance excessively of adjacent second yoke forming elements, a stretch eliminating anti-friction roller forming end for said contour departing element, and a yieldable mounting for the contour departing element in the second yoke whereby it may be forced backwardly independently of adjacent second 30 yoke carried forming elements in the forming action to attain the opposing abrupt bend contour of the first yoke forming means without gripping the spring being formed and stretching it at the abrupt bend 35 contour.

In testimony whereof I affix my signature in the presence of two witnesses.

HENRY POFFINBARGER.
